CONTAINER AND DISCHARGE VALVE
THEREFOR

Elmer C. Skousgaard, Los Angeles, Calif.

Application March 14, 1950, Serial No. 149,537

6 Claims. (Cl. 62—1)

1

The present invention is a continuation-in-part of my co-pending patent application, Serial Number 6,390, filed February 5, 1948, now abandoned, and relates generally to pressure vessels and containers for pressurized liquefied gases, more particularly liquefied petroleum gases and to an improved discharge valve therefor. It relates more particularly to an improved portable gas holding cartridge container and discharge valve, such as may be employed as a gas supply container in conjunction with a hand torch, portable stove and the like. It should be noted that the generic form of the present invention including a hollow casing, means for filling the casing with a liquefied, pressurized gas, outlet means connecting the interior of the casing with the exterior thereof, controllable valve means arranged to control flow through the outlet means, and pressure reducing means positioned within the outlet means whereby when the controllable valve means is open the pressurized liquefied gases will be forced through the pressure reducing means in the outlet means and will be virtually, completely vaporized, is more completely described, illustrated and claimed in my co-pending patent application, Serial Number 149,538, filed March 14, 1950.

Propane, butane and similar gases are transported in liquid form under pressure, but they quickly vaporize upon release of pressure. The conventional cartridge for liquefied petroleum gases has an opening in its bottom, through which the cartridge may be filled, and a centrally disposed outlet tube through which the gas may be discharged. Because of the location of the outlet tube, the conventional cartridge can be filled at most to slightly less than fifty percent of capacity. A further disadvantage of conventional cartridges, is that the liquefied gas in the outlet tube is likely to freeze in operation, preventing supply of the gas as required.

A primary object of the present invention is to provide an improved cartridge for liquefied petroleum gases which can be filled initially to a much greater percentage of volumetric capacity than can conventional cartridges.

Another object of the invention is to provide an improved cartridge for liquefied petroleum gases which is constructed so that the likelihood of the outlet duct being frozen is negligible.

Another object of the invention is to provide an improved cartridge for liquid petroleum gases having a simple control for governing the supply of gas from the cartridge to a torch, burner, or other device with which the cartridge is used.

Other objects of the invention will be apparent hereinafter from the specification and from the recital of the appended claims.

Fig. 1 is a side elevation, partly broken away, of a container or cartridge made according to one embodiment of this invention.

Fig. 2 is a fragmentary view on a greatly enlarged scale, showing the front or discharge end of the cartridge and its control valve.

Fig. 3 is a section on the line 3—3 of Fig. 1, looking in the direction of the arrows.

Fig. 4 is an elevation showing on a much reduced scale a cartridge fitted to and forming part of a hand torch.

Referring now to the drawings by numerals of reference, 10 denotes the cartridge cylinder or casing. Threaded into a central opening in the bottom end wall of this casing is a valve nipple 12. This nipple has a central port 13 in it which is adapted to be closed by a ball check valve 15 that is normally spring pressed into closed position by the coil spring 16. The spring 16 is interposed between the ball 15 and a nut 17 that threads adjustably into the inner end of the nipple. The nut 17 has a central bore 18 through which liquid may flow into the body of the cylinder 10 when the ball valve 15 is open.

A plug 20, that threads into a recess 21, formed in the outer end of the nipple 12, serves normally to seal the bottom of the casing. When this plug is removed from the casing, liquid propane or butane can, however, be pumped into the casing to fill the cartridge, the ball check valve 15 opening under pressure and the liquid gas flowing through the recess 21, port 13, open valve 15 and the duct 18 into the casing. If desired, the filling nozzle may be threaded into the nipple 12 in place of the plug 20 during the filling operation.

Welded or otherwise suitably secured in a central opening in the top end of the casing is a collar 25. This collar supports a sleeve 26 to which is secured a nipple 27. Adjustably threaded into a central bore 48 in the sleeve 26 is a valve member 30. This valve member has a conical nose 31 which constitutes the valve proper and which is adapted to seat in a port 32 that is drilled centrally in the sleeve 26 and which is adapted to communicate with bore 48. The valve comprising nose 31 and port 32 controls the rate of discharge of gas from the cartridge.

The liquid gas is delivered to the port 32 by a tube 35 whose front or upper end is secured by

a press-fit, or in any other suitable manner, centrally in the nipple 21. This tube is formed to provide a tortuous route for the passage of the liquid gas therethrough. It has a portion 36 which is bent away from the center of the cylinder to one side of the cylinder. The portion 36 communicates with another portion 37 of the tube which is bent back toward the center of the cylinder again. The portion 37, in turn, is connected by a loop 38 with a parallel inclined portion 39 that extends to the opposite side of the cylinder from the portion 36 of the tube. The tube is bent beyond the portion 39 into a plurality of loops 40 and it terminates in an inlet portion 41 which extends parallel to the axis of the cartridge but is offset from the axis of the cartridge close to one side of the cylinder.

The liquid gas passing through the tube 35 is delivered from the tube 35 into duct 45 in the nipple 21. Thence it passes into a filter chamber formed in the sleeve 26 which contains permeable filter means 46, which may consist of felt, fabric or any suitable permeable coarse material having a sufficient percentage of voids to allow the gas contained within the casing 10 to pass therethrough. The filter means 46 acts to both filter gas passing therethrough and to drop the pressure thereof in a manner facilitating complete vaporization thereof. This is also aided by the restricted ports. The port 32 in the sleeve 26 communicates with this expansion chamber. As already stated, the port 32 communicates with the bore 48 of sleeve 26 which constitutes another expansion chamber.

From the chamber 48 the gas flows through an angled, smaller diameter duct 49, that is drilled into valve member 30 alongside the base of the nose 31, into an elongated duct 50 drilled centrally in the valve member 30. A rod or bar 51 is mounted in this duct. The diameter of this rod or bar is slightly less than the internal diameter of the hole 50 so that the gas may flow around the outside of the rod between the rod and the inside surface of the hole 50. From the hole 50 the gas flows into a chamber 62a formed in the member 62 which is threadedly engaged within a chamber 53 formed in the enlarged head 54 non-integrally carried by the valve member 30. The chamber 62a contains an O-ring 62 adapted to sealingly connect the bore 50 and the chamber 62a and to effectively mechanically connect the head 54 and the valve member 30. The head 54 has a knurled peripheral surface by means of which it may be manually gripped for rotating the valve member 30 to open or close or to adjust the valve 31. The knurled head 54 is internally threaded to receive the externally threaded member 62 or a pipe or any other conducting means for supplying the gas to the stove, torch, or other unit, with which the cartridge is to be used.

In the drawing, the cartridge is shown as forming part of a portable burner, the burner head being denoted at 60 in Fig. 4. This head is connected by a supply tube 61 with a body member 62 which threads into the chamber 53 in the valve head 54. The tube 61 threads into an angularly disposed socket 63 formed in this body member; and this socket is connected with a central duct 65. When the body member 62 is threaded into the chamber 53, the duct 65 communicates with the chamber 62a and the bore 50. The body member 62 is provided with a lug or thumb piece 66 at one side by means of which it may be rotated.

To prevent leakage of the gas along the valve 30 and to insure that it follows the desired route through the valve stem, sealing members are provided at critical points. Thus, an O-ring seal 70, made of rubber or neoprene, is mounted in a peripheral recess 71 in the valve 30 to engage the inside wall of the recess or counterbore 72 which is formed in the upper end of the sleeve 26. Also there is mounted in the collar 25, above the sleeve 26, a supporting member 75 which surrounds valve member 30 and which carries in a peripheral recess an O-ring 76. This O-ring is interposed between member 73 and collar 25 and is adapted to seat against the top face of sleeve member 26. Also mounted in a recess or counterbore 77 of the supporting member 75 around the valve stem 30, is another O-ring 78. A jam nut 79, which threads into the bore 80 of the collar 25, serves to squeeze this O-ring between the member 75 and the periphery of the valve member 30 so as to prevent leakage along the outside of the valve member 30, and also serves to jam the O-ring 76 against the top or front face of the sleeve 26, to prevent leakage around the outside of the member 75. The three sealing rings 70, 76 and 78, therefore, insure that the liquid gas will not escape around valve member 30 or collar 75.

In addition to this sealing function, the O-ring 82 acts to clamp the body member 62, the head 54, and the valve member 30 together when the body member is fully threaded into the chamber 53 in the head 54. When this is done, the body member 62, the head 54, and valve member 30 will rotate together when the thumb piece 66 is pressed rotatably to adjust the opening of the valve member 31.

Because the inlet end of the tube 35 is disposed to one side of the central plane of the cylinder 10, the cylinder can be filled to more than fifty percent of capacity. In fact, in practice, it has been found possible to fill cylinders up to eighty-four percent of capacity with complete safety. The cartridge 10 is placed on its side, as shown in Fig. 1, with the inlet end 41 of the tube above the filling port in the bottom of the cartridge; the plug 20 is removed, and the liquid gas is pumped into the cartridge 10 to fill the cartridge up to a point where the liquid gas just begins to seep out of the ducts 50 through open valve 31. A steel cartridge can readily be made to take the pressure so built up in the casing without having to make its walls excessively thick. This means that a cartridge of a given size, made according to this invention, will have a capacity approximately seventy percent greater than a cartridge of conventional construction of the same size. A mark may be placed on the outside of the cylinder so as to insure that it is filled with the inlet end 41 of the tube 35 up, as shown in Fig. 1.

Another feature of the construction of this invention is that it eliminates a great many possibilities of the unit freezing up. The loops 40 and 38 in the tube 35 help prevent freezing. In addition, the liquid gas must also pass through restricting, pressure reducing means (including filter means 46) between the inlet end 41 of tube 35 and the outlet end of duct 50. Thus, the liquid gas passes from the tube 35 into a narrow duct 45, then into the relatively large chamber containing filter means 46, then into the narrow port 32 whose outlet opening is controlled by valve 31, then into relatively large chamber 48, then through narrow ducts 49 and 50 into rela-

tively large chamber 62a. This vaporizes the liquid.

After a cartridge has been filled to capacity, the valve 31 is closed by threading valve member 30 down in sleeve 26 until the valve seats tightly in port 32. The valve member can be manipulated by grasping knurled head 54. The filled cartridge acts as a storage tank for the liquid gas and the gas can be safely transported in it or stored until ready for use.

To use the cartridge it is simply coupled to the pipe or duct that leads to the torch, heater, stove, or other device in which the gas is to be consumed. The restrictive, pressure reducing means in the system will convert liquid to gas as required by the burner.

When the cartridge is used with a burner in the form of a torch, such as shown in Fig. 4, the body member 62 is tightly threaded into the knurled head 54 so that body member 62, the knurled head 54, and the valve member 30, will rotate together when the body member is rotated. After opening valve 31 by pressing on thumb piece 66, the burner can be lighted. Slight pressure in either direction on thumb piece 66 then easily and closely controls the flow of gas in the torch and the size of the flame, or permits the gas to be shut off entirely.

The rod 51 is used because it is much easier to drill a large diameter hole 50 than a small diameter hole, and because by suitable selection of the diameter of the rod the dimension of the duct formed between the rod and bore 50 can be controlled much more precisely and easily than if a small diameter duct only were drilled. Rod 51 may be provided with a bend or with teats (not shown) to hold it centered in the bore 50 and so that it will not fall out.

If the valve gets stuck or dirt gets into the valve seat or if the valve has to be removed for any reason, the removal of the jam nut 79 permits the whole assemblage of sleeve 26, collar 75 and valve member 30 to be lifted out of the casing and replaced, which is a great convenience.

While the invention has been described in connection with a specific embodiment thereof, it will be understood that it is capable of further modification and this application is intended to cover any variations, uses, or adaptations of the invention, following, in general, the principles of the invention and including such departures from the present disclosure as come within known or customary practice in the art to which the invention pertains and as may be applied to the essential features hereinbefore set forth and as fall within the scope of the invention or the limits of the appended claims.

I claim:

1. A cartridge container for liquefied petroleum gases and the like, comprising: a hollow casing; a sleeve mounted in said casing, said sleeve having a valve port in its inner end through which gas may pass out of the casing; a cylindrical valve member adjustably threaded into the sleeve to control the opening of said valve port; a resilient sealing member between the valve and the sleeve; a sealing ring surrounding the valve member and carrying two resilient sealing members positioned respectively to prevent escape of gas between the sleeve and the casing and between the valve member and the ring, and a nut removably threaded into the casing to force said two last named sealing members into operative positions; communicating

means connecting the valve port with the interior of the casing; and flow restricting, pressure reducing means in the communicating means.

5 2. A cartridge container for liquefied petroleum gases and the like, comprising: a hollow casing; a sleeve member mounted in said casing; a nipple secured in one end of said sleeve member; a tube connected to said nipple for conducting gas from the interior of said casing to the nipple, said nipple having a port extending through it which communicates at one end with the tube and is of smaller diameter than the interior diameter of the tube; said sleeve also having a chamber formed therein communicating with the other end of said port and of considerably greater diameter than said port; flow restricting, pressure reducing filter means positioned in said chamber; said sleeve having a port therein leading from said chamber, said second port connecting said chamber with a second chamber formed in the sleeve; a valve member threaded into the second chamber and having a valve portion seating in said second port to control discharge of the gas from said casing; said valve member having a central outlet bore formed therein; and a duct formed in said valve member at one side of said valve portion to connect said second chamber with said bore, said duct being of smaller diameter than said second chamber.

3. A cartridge container for liquefied petroleum gases and the like, comprising: a hollow casing; a sleeve member mounted in said casing; a nipple secured in one end of said sleeve member; a tube connected to said nipple for conducting gas from the interior of said casing to the nipple, said nipple having a port extending through it which communicates at one end with the tube and is of smaller diameter than the interior diameter of the tube; said sleeve also having a chamber formed therein communicating with the other end of said port and of considerably greater diameter than said port, flow restricting, pressure reducing filter means in said chamber; said sleeve having a port therein leading from said chamber and of smaller diameter than said chamber, said second port connecting said chamber with a second chamber formed in the sleeve and of larger diameter than the second port; a valve member threaded into the second chamber and having a valve portion seating in said second port to control discharge of the gas from said casing, said valve member having a central outlet bore formed therein; and a duct formed in said valve member on one side of said valve portion to communicate said second chamber with said bore, said duct being of smaller diameter than said second chamber; said tube having an inlet end at one side of the center line of said casing.

4. A cartridge container for liquefied petroleum gases, including a supporting member mounted therein provided with a central port for discharge of gas from within said container; a valve member rotatably threaded into said supporting member and having a valve portion formed integral therewith which seats in said port and controls the opening thereof, said valve member being longitudinally bored and having a duct formed therein at one side of the valve portion to conduct gas from said port to said bore; a coupling member threaded into said valve member for connecting said bore with the apparatus in which the gas is to be consumed, said coupling having a manipulating lug thereon whereby it

may be rotated, said coupling member having a duct therethrough through which the gas may flow from the bore of the valve member to said gas consuming apparatus; chamber means in the supporting member in communication with the port means; and permeable filter means carried in the chamber means under a selected compression such that virtually all liquefied petroleum gases passing therethrough will be virtually completely vaporized.

5. A device of the character defined in claim 4, including means interposed between the coupling member and the valve member for resiliently clamping the coupling member to the valve member so that the two rotate together.

10. A cartridge container for liquefied petroleum gases, comprising: a cylindrical casing having a central port in its base through which liquid gas may be supplied to the casing; means for closing said port; a supporting member disposed centrally in the other end of the casing and having a port through which gas may be discharged from within said casing; a valve member rotatably threaded into said supporting member and having a valve portion adapted to seat in said port; a 15 duct extending axially of said valve member; a

duct at one side of said valve member connecting the first named duct with said port; and a knurled head formed on said valve member externally of said casing for manipulation of said valve member; chamber means in the supporting member in communication with the port means; and permeable filter means carried in the chamber means under a selected compression such that virtually all liquefied petroleum gases passing therethrough from within the interior of the casing will be virtually completely vaporized.
